UNITED STATES PATENT OFFICE.

WILSON A. AUSTIN, OF OMAHA, NEBRASKA, ASSIGNOR OF ONE-HALF TO A. T. AUSTIN, OF OMAHA, NEBRASKA.

RAILWAY-SWITCH OR THE LIKE.

1,090,188.

Specification of Letters Patent. Patented Mar. 17, 1914.

Application filed January 31, 1910. Serial No. 541,018.

To all whom it may concern:

Be it known that I, WILSON A. AUSTIN, a citizen of the United States, residing at Omaha, in the county of Douglas and State 5 of Nebraska, have invented certain new and useful Improvements in Railway-Switches or the like, of which the following is a description.

My invention belongs to that class of devices known as railway switches or the like and relates more particularly to a coupling or connection between the throw rod for operating the movable rail part, or said movable rail part in a railway switch, derail 10 or the like and the actuating mechanism. It is particularly adapted for use for connecting the motor shaft and throw rod in an electrically operated switch or derail, changing the rotary movement of the motor 15 shaft into a longitudinal movement of the throw rod as well as permitting the acceleration of the motor before taking up its load in moving the switch points. It is also provided with means for preventing shocks to 20 the motor at the beginning and end of the movement of the rail parts.

The device may be used to great advantage in a system similar to that described in my pending application filed October 14, 30 1909, Serial No. 522,553, but it should be distinctly understood that the use of the connection is not confined to switch mechanisms or the like, as it is obvious that the same may be used wherever it may be found 35 applicable.

My invention has among its objects the production of a simple, convenient, efficient and satisfactory device of the kind described.

To this end my invention consists in the novel construction, arrangement and combination of parts herein shown and described, and more particularly pointed out in the 40 claims.

Referring to the drawings in which like reference characters indicate like or corresponding parts, Figure 1 is a plan view of the motor, throw rod and connecting means, Fig. 2 is a sectional view taken substantially 45 on line 2—2 of Fig. 1, Fig. 3 is a sectional view taken substantially on line 3—3 of Fig. 2, Fig. 4 is an enlarged sectional view of a portion of the connection or coupling, Fig. 5 is a sectional view taken substantially on

line 5—5 of Fig. 4, Fig. 6 is a sectional view 55 taken substantially on line 6—6 of Fig. 4, Fig. 7 is a perspective view of the part 32 looking in a direction indicated by the arrows 7—7 in Fig. 4, Fig. 8 is a perspective view of the part 31 looking in a direction 60 indicated by the arrows 8—8 in Fig. 4, and Fig. 9 is a sectional view taken substantially on line 9—9 of Fig. 4. Fig. 10 is a diagrammatic view showing one way of electrically connecting and operating the switch or de- 65 rail.

Referring to the drawings, the switch mechanism casing 13 is shown in which the coupling or connection is arranged. The motor 14 is provided with a suitable driving shaft 27 and the throw rod is represented by the numbers 12 and 24, it being understood that the same is suitably connected to the movable rail part 4¹ in any suitable way, as for example, as shown in my application previously mentioned, so that longitudinally moving the throw rod moves the rail part to which the same is secured. The arrangement would be substantially the same for the movable part in a derail. 80

The present invention relates particularly to means for connecting the motor shaft 27 and the throw rod 24 so that the rotary movement of the motor shaft is transformed into a longitudinal movement of the throw 85 rod, the same being preferably arranged so that the motor armature may rotate a turn or so before picking up the load, the load being picked up and dropped without any shock to the motor shaft. 90

Referring particularly to Figs. 1 and 2, 1 is a shaft suitably connected with the motor shaft 27, preferably in a manner hereinafter described and arranged to be driven thereby. The shaft 1 is threaded as indicated at 5 95 and arranged to coöperate with a suitable sleeve 6 arranged on the rod 24, the sleeve being shown separable from the rod and secured thereto by means of a pin 7. It will thus be seen that this connection is substantially a threaded bolt arranged on one part and a coöperating engaging part arranged on the other part, as shown, on the rotating part and movable rod respectively. Any equivalent construction may be employed 100 for the purpose, or the sleeve modified as desired. It is of course obvious that as the shaft 1 is rotated in one direction or the

other, the same being prevented from moving longitudinally as hereinafter described, the sleeve 6 secured to the rod 24 will travel along the shaft 1 so that the throw rod is 5 positively and directly moved longitudinally, thereby moving the movable rail part. Any suitable means may be employed for preventing rotation of the rod 24, a suitable key 43 engaging the sleeve 6 being shown 10 for the purpose.

My preferred construction for permitting the acceleration of the motor armature before picking up the load and preventing any shock on the motor at the beginning or end 15 of the travel of the movable rail part, is most clearly shown in Figs. 4 to 8. Referring to these figures, 8 is a suitable member arranged on and secured to the shaft 27 by means of a pin 9 or the equivalent for the 20 purpose. The shaft 1 is suitably supported by means of a bracket or bearing 2 carried by the casing 13 or by its equivalent for the purpose. On the shaft 1 is arranged a plurality of members, the member 17 being secured to the shaft and preferably extended as shown at 30 and provided with a suitable pin 38 or its equivalent. Parts 19, 20, 21, 23, 25 35, 26 and ball bearings 22 and 28 are also preferably provided at the bearing 2 and arranged to coöperate with the shoulder on the shaft 1 and the member 17 to prevent friction due to the thrust of the shaft 1 during the operation of the device. Any equivalent means may be provided for the purpose. On the 30 extension 30 are preferably arranged members 31 and 32. The member 31 is provided with slots 39 and 41 preferably on each side thereof, as shown, and the member 32 is provided with a pin 40 preferably extending through each side thereof. The pin 38 on the member 17 is arranged to extend into the slot or groove 39, while one end of the pin 40 extends into the slot 41. Also arranged on the shaft 1 and preferably extending over, as at 34, is a member 33 provided with a suitable slot or groove 42 arranged to coöperate with the pin 40. Suitable plates 11 and 15 are arranged on the extension 34, a portion of the same being 35 40 45 50 55 60 65 70 75 80 85 90 95 100 105 110 115 120 125 130 extended and notched and arranged to co-operate with the extensions 10 of the member 8 (see Figs. 4 and 5). A collar 36 loosely arranged on the extension 34 is normally maintained in contact with the desired disk by means of a resilient member 37 co-operating with the collar 35, the several parts forming a friction clutch.

Any suitable mechanism may be employed 60 for controlling the motor, the preferred construction comprising mechanism substantially similar to that mentioned and described in my pending application before referred to or in the application of Charles O. Anderson, Serial No. 523,078, filed October 16, 1909. Referring to the drawings,

mechanism somewhat similar to that described in my own application is shown in part in detail and in the diagrammatic view in Fig. 10. In the present application, however, suitable switch members 44 and 45 are provided, the same being shown arranged within and adjustably carried by the casing 13. As most clearly shown in Figs. 1, 2, 3 and 10, the members 44 and 45 carry suitable switch members 55 and 55¹ and contact members 50, 51, 52 and 53, and 50¹, 51¹, 52¹ and 53¹. A suitable movable member 46 (similar to member 28 in my application mentioned) is carried by the throw rod 8, the same being suitably secured to the sleeve 6 by a bracket 47 or its equivalent for the purpose. The movable member 46 carries contact pieces 48 and 49 which coöperate with the contact members 50, 51, etc., and is also arranged to operate suitable pins 57 and 57¹ which control the switch members 55 and 55¹ (the pins 57 and 57¹ are indicated diagrammatically in Fig. 10 by the small extensions 57 and 57¹). As the throw rod travels in one direction or the other the member 46 carried thereby opens and closes certain circuits, as more fully described in the operation of the device. A suitable pole changer "P" is also provided (shown diagrammatically in Fig. 10), the same being suitably connected with the motor, the switch members just mentioned and the tower or controlling point. Briefly, the pole changer may be said to consist (referring to Fig. 10) of suitable solenoids 58 and 58¹ which control suitable switch members 68 and 68¹ which coöperate with suitable contact points and close or open the circuits as more fully explained in the operation of the device.

It might be noted that the apparatus at the tower T may be of any suitable form, a double throw switch being shown for opening and closing the several circuits, the preferred construction comprising an arrangement in which only one circuit may be closed at the same time. Also the indicating apparatus shown in Fig. 10 at the tower is indicated diagrammatically by the coil 119, it being understood that any suitable apparatus applicable for the purpose may be used.

The reference character "B" indicates a battery, dynamo or any equivalent or suitable source of power.

The operation of the device may be briefly described as follows: Assuming for example the electrical connections to be as mentioned, the proper operating circuit is closed so that the motor is driven in the required direction. As the parts are shown in Figs. 1 and 2, the movable rail part 4¹ is in what I have heretofore called a reverse position, that is, at the limit of its travel away from the motor. Referring then to

the diagrammatic view, Fig. 10, three wires 94, 89 and 123 lead from the point from which the apparatus is controlled, as for example from the switch, to the tower mechanism. The movable rail part being in the position shown the member 46 carrying the contact members 48 and 49 is in its position making contact between members 50¹ and 51¹ and 52¹, 53¹, switch 55¹ being open. Assuming that the main switch "S" at the tower is thrown as indicated by the dotted lines in Fig. 10, thereby closing what may be termed the normal controlling or operating circuit which includes conductors 123 and 94, which last mentioned conductor is common to both circuits. Starting from the battery or dynamo "B" the circuit may then be traced as follows: B, 86, 87, 128, 123, 129, 56, 55, 130, 58¹, 131, 93, 94, 95 and B. This energizes solenoid 58¹ and raises member 68¹, contact member 82 closing a circuit between contact points 78 and 80 and contact member 83 closing a circuit between contact members 79 and 81. The motor operating circuit may then be traced as follows: B, 86, 87, 128, 123, 124, 78, 82, 80, 122, 107, 106, 105, 104, 103, armature A, 102, 101, 100, 99, 98, 133, 79, 82, 81, 134, 110, 111, 112, 113, 114, 115, 94, 95 and B. This causes the motor to operate in the reverse direction throwing the movable rail parts toward the motor. At the limit of their travel contact is broken between members 55 and 56, breaking the circuit which energizes the solenoid 58¹. Member 68¹ therefore drops, breaking the motor circuit last mentioned and closing the indicating circuit between points 84 and 85 so that the indicating circuit may then be traced as follows: armature A, 103, 104, 105, 106, 135, 51, 48, 50, 136, 85, 82, 84, 137, 64, 96, 89, 138, 121, 120, 119, 118, 94, 115, 114, F, 113, 112, 111, 139, 53, 49, 52, 140, 99, 100, 101, 102, armature A, thus indicating that the switch or derail has been closed. The motor being operated as mentioned or as shown in the drawings, in the direction of the arrow shown in Fig. 6, the member 33 driven through the friction clutch will then rotate until the pin 40 is engaged at the opposite end of the slot 42, whereupon the member 32 will be rotated carrying the pin 40 around until the opposite end of the pin engages the opposite end of the slot 41 in the member 31. The member 31 will then be rotated until the opposite end of the slot 39 engages the pin 38 in the member 17, thereby rotating the shaft 1 to which the same is secured. The shaft 1 being driven and maintained against longitudinal movement as mentioned will throw the sleeve 6 in one direction or the other depending upon the thread 5, as shown toward the motor 14, thereby moving the movable switch part or derail. It will thus be seen that the motor takes a turn or so before picking up its load. Owing to the friction clutch mentioned it will also be noted that the motor does not pick up its load with a shock, nor is it abruptly stopped when the switch points or derail reach the end of travel and the operating circuit is broken. It is obvious that the motor shaft 27 might be connected directly to the shaft 1 or be formed integral therewith, or that the friction clutch mentioned might be arranged directly within shaft 27 and shaft 1 and the slot and pin connection omitted. The circuits for throwing the throw rod in the opposite direction, assuming them to be at the left of the last operation, may be traced as follows: The switch "S" at the tower is thrown as shown in the full lines in Fig. 10, thereby closing the reverse controlling or operating circuit which includes conductors 89 and 94. Starting from the battery or dynamo "B" the circuits may be traced as follows: B, 86, 87, 88, 89, 90, 56¹, 53¹, 91, solenoid 58, 92, 93, 94, 95 and B, energizing solenoid 58 and raising member 68 closing the circuits through 64, 66 and 62 and 65, 90 67 and 63. This closes the motor circuit which may be traced as follows: B, 86, 87, 88, 99, 64, 66, 62, 97, 98, 99, 100, 101, 102, armature A, 103, 104, 105, 106, 107, 108, 65, 67, 63, 109, 110, 111, 112, 113, fields F, 95 114, 115, 94, 95 and B. This causes the motor to operate and rotate shaft 27 in a reverse direction than heretofore described, thus moving the throw rod in the opposite direction through the various connections heretofore mentioned in substantially the same manner. When the movable rail part reaches the limit of travel the member 46 operates the pin 57¹, thereby operating the switch member 55¹ and breaking the circuit 100 energizing the solenoid 58. This circuit being broken the member 68 drops, breaking the several circuits at points 64 and 62, and 65 and 63 and closing a circuit between contact points 73 and member 66 and contact point 72. The indicating circuit may be traced as follows: armature A, 102, 101, 100, 116, 52¹, 49, 53¹, 117, 112, 113, F, 114, 115, 94, 118, 119, 120, 121, 122, 123, 124, 78, 125, 72, 66, 73, 126, 51¹, 48, 50¹, 127, 105, 104, 103 115 and armature A, thus giving the signal. The movable rail part may be reversed during its operation in exactly the same way as in my application mentioned and in case the switch points accidentally move 120 so that the switch points or movable rail part and the stock rails or fixed part become accidentally spread or separated, the switch or derail will be automatically operated, as also mentioned in my application. 125 The members 44 and 45 may be adjusted relatively to the stock rails as desired or found necessary, it being unnecessary in the case of a switch having two switch points to adjust the points relative to each other 130

so that a solid spreader bar between the switch points may be used.

Having thus described my invention it is obvious that various immaterial modifications may be made in the construction and arrangement of the parts shown and described without departing from the spirit of my invention, hence I do not wish to be understood as limiting myself to the exact construction, arrangement or combination of parts herein shown or described or uses mentioned.

What I claim as new and desire to secure by Letters Patent is:

15. 1. In a device of the kind described and in combination, a rotating part, a switch part movable longitudinally of said rotating part, a threaded bolt carried by one part and a coöperating engaging member carried by the other part, and means for positively connecting said rotating part with the part carried thereby after a predetermined rotation of said rotating part.

25. 2. In a device of the kind described and in combination, a rotating part, and a longitudinally movable part, a threaded bolt, means for connecting said bolt to the rotating part after a predetermined rotation thereof, and means carried by said longitudinal movable part for engaging said threaded bolt.

35. 3. In a device of the kind described and in combination, a rotatable part and a longitudinally movable switch part and means for transmitting the rotary motion of said rotatable part to said other part to longitudinally move the same, comprising an externally threaded member, means for positively connecting said member with said rotatable part after a predetermined rotation of said part, and an internally threaded part secured on said switch part and movable therewith.

45. 4. In a device of the kind described and in combination, a driving shaft and a throw rod, means for operatively connecting said shaft and throw rod, said means comprising a rotatable shaft positively connected with said throw rod and means for operatively connecting the same with said driving shaft after a predetermined rotation of said driving shaft.

55. 5. In a device of the kind described and in combination, a plurality of rotatable shafts, means arranged therebetween for positively connecting the same, said connecting means normally inoperative until a predetermined rotation of the driving shaft in either direction, and comprising a plurality of disks connected by slot and pin connections.

65. 6. In a device of the kind described and in combination, a rotating part, a switch part movable longitudinally of said rotating part, a threaded bolt carried by one part and a coöperating member carried by

the other part, means for driving said rotating part comprising a driving shaft and means for operatively connecting said shaft and said rotating part after a predetermined rotation of the driving shaft.

7. In a device of the kind described and in combination, a rotating part, a switch part movable longitudinally of said rotating part, a threaded bolt carried by one part and a coöperating member carried by the other part, means for driving said rotating part comprising a driving shaft and means for frictionally connecting said shaft and said rotating part after a predetermined rotation of the driving shaft.

75. 8. In a device of the kind described and in combination, a rotating part and a longitudinally movable part and means for operatively connecting the same and driving means for said rotating part arranged to operatively engage the part after a predetermined acceleration of the driving means.

80. 9. In a device of the kind described and in combination, a longitudinally movable rod, a rotating shaft operatively connected therewith by substantially a bolt and nut connection and driving means for said rotating shaft comprising a driving shaft and slot and pin connecting means operatively arranged therebetween.

85. 10. In a device of the kind described and in combination, a longitudinally movable switch throw rod, a rotatable shaft, means for operatively connecting the same, means for driving said shaft in either direction comprising a motor shaft operatively connected thereto by a pin and slot connection.

90. 11. In a device of the kind described and in combination, a longitudinally movable switch throw rod, a rotatable shaft, means for operatively connecting the same, means for driving said shaft in either direction comprising a driving shaft and means for operatively connecting said shafts, said means comprising friction mechanism and a slot and pin connection.

105. 12. In a device of the kind described and in combination, a longitudinally movable switch throw rod, a rotatable shaft, means for operatively connecting the same, means for driving said shaft in either direction comprising a driving shaft, connecting means for said shafts, said means arranged to permit a predetermined rotation of the driving shaft before operative engagement with the said rotatable shaft.

115. 13. In a device of the kind described and in combination, a rotating part, a longitudinally movable part and means for operatively connecting the same and driving means for said rotating part arranged to frictionally engage the part after a predetermined acceleration of the driving means.

125. 14. In a device of the kind described and in combination, a driving shaft and a longi-

- tudinally movable rod and means for operatively connecting the two, said means comprising a rotatable shaft operatively connected to said driving shaft arranged to 5 permit the acceleration of the driving shaft before the operative engagement with said shaft and means for connecting said shaft and said throw rod comprising coöperating threads on said parts.
- 10 15. In a device of the kind described and in combination, a driving shaft, a longitudinally movable rod, an auxiliary shaft, means for operatively connecting said auxiliary and said driving shaft after the driving shaft has rotated a predetermined distance and means for operatively connecting said shaft and throw rod.
- 15 16. In a device of the kind described and in combination, a rotatable shaft, an auxiliary shaft, means for connecting said shafts comprising friction mechanism and means for operatively engaging said friction mechanism and said auxiliary shaft after a predetermined rotation of said driving shaft.
- 20 17. In a device of the kind described and in combination, fixed and movable rail parts, a throw rod for said movable parts, a rotatable shaft, means for operatively connecting said shaft and throw rod, said means arranged to permit a rotation of said shaft before operative engagement with said rod, driving means for said shaft and controlling means therefor operated by said throw rod.
- 25 18. In a device of the kind described and in combination, fixed and movable rail parts,
- 30 35 a throw rod for said movable parts, a rotatable shaft, means for operatively connecting said shaft and throw rod, said means arranged to permit the acceleration of said shaft before operative engagement with said rod, means for driving said shaft and mechanism for controlling said driving means, said mechanism controlled by said throw rod.
- 35 19. In a device of the kind described and in combination, a shaft and means for driving the same in either direction, a longitudinal movable rod, a rotatable shaft provided with threads on one end thereof, means for positively connecting said shafts after a predetermined rotation of said first mentioned shaft, comprising a plurality of parts connected by a slot and pin connection, one of said parts secured to said second mentioned shaft, and another of said parts yieldingly secured to said first mentioned shaft, and means for connecting said second mentioned shaft to said rod comprising an internally threaded part in threaded engagement with said second mentioned shaft, and means for securing said part to said rod.
- 40 45 50 55 60 65 In testimony whereof, I have hereunto signed my name in the presence of two subscribing witnesses.

WILSON A. AUSTIN.
